CONTROL APPARATUS

Henry S. Young, Wilkinsburg, Pa., assignor to
The Union Switch & Signal Company, Swiss-
vale, Pa., a corporation of Pennsylvania

Original application November 26, 1941, Serial No.
420,487. Divided and this application Decem-
ber 2, 1942, Serial No. 467,619

3 Claims. (Cl. 246—3)

My invention relates to control apparatus, and has particular reference to the organization of such apparatus into remote control or train dispatching systems of the class wherein traffic controlling functions located at a field station are governed by controls transmitted from a remote office station over a communication system. More particularly, my invention relates to train dispatching or centralized traffic controlling systems of the class wherein remote control of railway track switches is effected by means of switch operating mechanisms having a dual selector operative to one position for conditioning the associated track switch for manual operation and to another position for conditioning the track switch for operation by the switch operating machine.

My invention is applied to a train dispatching or centralized traffic controlling system of the class involving control relays of the polar type effective when deenergized to retain their polar armatures in the last operated position, and which systems are arranged to position the polar armatures of the control relays in response to energy momentarily applied to such relays in response to controls transmitted from a remote office over a communication system. One such system of this type is shown, for example in Letters Patent of the United States No. 2,273,231, granted February 17, 1942, to Clarence S. Snavely and Alfred B. Miller.

An object of my invention is the provision, in a system of the class described, of novel and improved means arranged to require a control to be transmitted from the office to the field station in order to obtain operation of a track switch by a switch operating mechanism following a restoration of the selector lever to its power operating position after the selector has been moved to its manual operating position.

Another object is the provision in a system of the class described, of novel and improved means for preventing automatic operation of a track switch by a switch operating mechanism in the event that the selector lever is restored to its power operating position after the track switch is manually operated to a position out of correspondence with the remotely controlled apparatus.

The above-mentioned and other important objects and characteristic features which will become readily apparent from the following description, are attained in accordance with my invention by employing a stick relay normally energized over a stick circuit controlled by a

contact closed only in the motor operating position of the dual selector lever; by including a front contact of the stick relay in the circuit over which the switch operating relay is controlled by the remotely controlled switch control relay; and by providing the stick relay with a pick-up circuit completed only when the track switch and the remotely controlled switch control relay are in positions of correspondence.

10 The present application is a division of my copending application, Serial No. 420,487, filed on November 26, 1941, for Control apparatus.

I shall describe one form of apparatus embodying my invention and shall then point out the novel features thereof in claims.

The accompanying drawing is a diagrammatic view illustrating one form of apparatus embodying my invention.

Referring to the drawing, the reference character CW designates a crossover provided at opposite ends with two track switches, designated by the reference characters W with suitable distinguishing suffixes, each operatively connected with a dual selector type of switch operating mechanism. The operating mechanism associated with switch W1, for example, comprises a dual selector lever S1 which operates a link 1. When selector lever S1 is in its normal or power operating position, as shown in the drawing, link 1 conditions the switch for operation by a power switch operating mechanism SMI, and when lever S1 is in its reverse position, the link conditions switch W1 for operation by a manually operable lever H. Operatively connected with link 1 is a contact member 6 which is operated into engagement with another contact member 7 when and only when lever S1 is in its power operating position. The switch W1 also is operatively connected with a contact member 8 which is operated into engagement with a set of contacts 9 or 10 according as the switch is in its normal or reverse position respectively. The operating mechanism associated with track switch W2 is similar to the operating mechanism just described for switch W1, as can be seen from an inspection of the drawing, and further detailed explanation is deemed unnecessary.

The power operating switch mechanisms SMI and SM2 may be of any suitable type, such as, 50 for example, electric or electropneumatic switch machines. The switch mechanisms are controlled in accordance with the usual practice by switch control means comprising a polarized relay WR and it is deemed sufficient to state that when relay WR is energized by current of normal

or one relative polarity to close its front contact 14 and operate its polar armature 15 to its normal position, or left-hand position as viewed in Fig. 1, switch mechanisms SM1 and SM2 are caused to operate their associated switches to their respective normal positions, and that when relay WR is energized by current of reverse polarity to close its front contact 14 and operate its polar armature 15 to its reverse or right-hand position, the switch mechanisms are then caused to operate their associated switches to their respective reverse positions.

The reference character WS designates a control relay for controlling switch operating relay WR. Relay WS is a polar relay of the polar stick type that when deenergized retains its polar armature in its last operated position, and as shown in the drawing, relay WS has two windings, one winding of which when energized is capable of positioning the polar armature of the relay in one of its extreme positions and the other winding of which when energized is capable of positioning the polar armature in its other extreme position.

Relay WS is manually controlled from a central office in a well-known manner by means of any suitable communication or centralized traffic control system, such as for example, that shown in the aforesaid Snavely and Miller Patent No. 2,273,231. For the purposes of the present description, it is deemed sufficient to state that the polar armature of relay WS is positioned in one extreme position in response to energy applied momentarily to one of its two windings in response to a characteristic control code transmitted from the office to the field station, and is positioned in the other extreme position in response to energy momentarily applied to the other of its two windings in response to a characteristically different control code transmitted from the office to the field station.

The reference characters SR with suitably distinguishing suffixes designate two stick relays one for each track switch W1 and W2. Each stick relay is provided with a pick-up circuit completed when and only when the associated switch occupies a position, indicated by the associated switch operated contact member 8, in agreement with the position of the polar armature of control relay WS. For example, when the polar armature of relay WS is in its left-hand position and switch W1 occupies its normal position, relay SR1 is provided with a pick-up circuit extending from one terminal B of a suitable source of current, such as a battery not shown, through polar contact 36 of relay WS, closed in the normal or left-hand position of the polar armature of relay WS, contact 9-8-9 operated by switch W1 and closed in the normal position of the switch, the winding of relay SR1 and contacts 1-6 of selector levers S1 and S2, respectively, to the other terminal C of the same source of current. Similarly, when switch W2 and the polar armature of relay WS are in their respective normal positions, relay SR2 is then provided with a pick-up circuit which extends from terminal B through polar contact 36 of relay WS closed in the left-hand position of the polar armature of relay WS, contact 9-8-9 operated by switch W2 and closed in the normal position of that switch, the winding of relay SR2, and contacts 1-6 of selector levers S1 and S2, respectively, to terminal C. These stick relays cooperate with relay WS in the control of operating relay WR to require a control to be

transmitted from the office to the field station in order to obtain operation of a switch by a switch machine following a restoration of the selector lever to its power operating position after the selector has been moved to its manual operating position.

In the normal condition of the apparatus, as represented in the drawing, selector levers S1 and S2 are in their respective normal or power operating positions to condition the associated switches for operation by the power operating switch mechanisms; selector lever contacts 6-7 are closed; stick relay SR1 is energized over a stick circuit extending from terminal B through its own front contact 59 and winding, and selector lever contacts 7-6 to terminal C; stick relay SR2 is energized over a stick circuit extending from terminal B through front contact 51 and the winding of relay SR2, and selector lever contacts 6-7 to terminal C; switch operating relay WR is energized by current of one relative polarity over a circuit extending from terminal B through front contact 34 of relay SR2, front contact 35 of relay SR1, polar contact 18 of relay WS in its normal or left-hand position, as viewed in the drawing, front contact 19 controlled by the electric locking apparatus ordinarily incorporated into switch control apparatus, the winding of relay WR, front contact 20 controlled by the electric locking apparatus, and polar contact 21 of relay WS in its normal position to terminal C. The polarity of current supplied at this time to relay WR is such as to cause that relay to operate its polar armature to a position in agreement with the position of the polar armature of relay WS. Each track switch W1 and W2, as pointed out hereinbefore, occupies a position depending upon the position of the polar armature of relay WR, and hence each track switch also agrees in position with the position of control relay WS.

Operation of the track switches may be remotely controlled, as is the usual custom, by the operator at the office station causing a characteristic code to be transmitted over the communication system to position the polar armature of relay WS in its other extreme position. When this happens, relay WS reverses the position of its polar armature to reverse the polarity of current energizing switch operating relay WR, as is readily apparent from an inspection of the drawing, and as a result relay WR reverses its polar armature 15 to cause each track switch W1 and W2 to be operated by its associated power switch operating mechanism to its other extreme position, wherein each switch W1 and W2 agrees in position with both switch operating relay WR and switch control relay WS. The track switches W1 and W2 may of course be restored to their respective normal positions by the operator causing the characteristic code corresponding to the normal position of relay WS to be transmitted over the communication system.

The track switches W1 and W2 may also be locally operated by a trainman. To do this, a selector lever is first moved to its manual operating position to condition the associated switch for manual operation. For example, if lever S1 is moved to its manual operating position, contact 6-7 associated with that lever is opened to interrupt the previously traced stick circuits of both relays SR1 and SR2, whereupon front contacts 34 and 35 open and thereby remove relay WS from control of switch operating relay WR. It is apparent, therefore, that remote

control of the switches will be prevented at this time should a control be transmitted to a field station in an attempt by the operator to effect operation of the switches. Local operation of switch W1 may, however, be attained by the trainman operating manual operating lever H associated with that switch. After manual operation of that switch has been completed, the selector lever may be restored to its normal or power operating position to condition the switch for operation by the switch mechanism. When this happens, contact 6-7 associated with selector lever S1 will close, and stick relays SR1 and SR2 will pick up over their respective pick-up circuits provided that the position of the associated switch agrees with the position of control relay WS. For example, assume that relay WS is in its normal or left-hand position, and that selector lever S1 is moved to its hand operating position, thereby opening its associated contact 6-7 and causing both relays SR1 and SR2 to release. After switch W1 is manually operated to its reverse position, wherein switch operating contact 10-8-10 is closed and contact 9-8-9 is opened, a restoration of selector lever S1 to its normal position results in relay SR2 picking up over its previously traced pick-up circuit, but relay SR1 remains released. As a result, switch operating relay WR also remains released, and operation of switch W1 by power to its normal position in correspondence with switch operating relay WR and switch control relay WS will be prevented.

Relay SR1 may be picked up, to restore control relay WS to control of operating relay WR, by the operator dispatching a code to relay WS to cause that relay to operate its polar armature to a position of correspondence with switch W1. When this happens, relay SR2 remains energized over its stick circuit while relay SR1 becomes energized over a circuit extending from terminal B through polar contact 36 in its reverse or right-hand position, contact 10-8-10 operated by switch W1, the winding of relay SR1, and contacts 6-7 operated by selector levers S1 and S2, respectively, to terminal C, and relay SR1 accordingly picks up to close its front contact 35 interposed in the energizing circuit of operating relay WR. Relay WR now becomes energized by current having a polarity such as to cause the polar armature of such relay to operate to its reverse position, whereupon switch mechanism SM2 becomes energized and causes the other switch W2 to operate to its reverse position. To restore the switches to normal, the operator may send the normal code to relay WS to cause that relay to restore its polar armature to its normal position, whereupon relay WR operates to a position in agreement with relay WS and energizes mechanisms SM1 and SM2 to cause such mechanisms to operate switches W1 and W2 to their respective normal positions in agreement with relays WR and WS.

The switch mechanisms represented in the drawing are preferably of the electropneumatic type, hence no overload protection is provided. Should electric switch movements be employed, however, the apparatus may be modified to incorporate overload protection, which protection may be provided in any suitable manner, as for example the manner shown and covered in Letters Patent of the United States No. 2,199,952, granted on May 7, 1940 to Claude M. Hines and Bernard E. O'Hagan. In addition, it is to be understood that the apparatus may be modified

to control but a single switch, in which event only one stick relay, such as relay SR1, and one switch mechanism, such as mechanism SM1, would be required.

5 Although I have herein shown and described only one form of control apparatus embodying my invention, it is understood that various changes and modifications may be made therein within the scope of the appended claims without departing from the spirit and scope of my invention.

Having thus described my invention, what I claim is:

1. In a train dispatching system for railroads, 15 the combination with a track switch, a switch machine provided with a dual selector for selectively conditioning said switch for operation manually or by said machine, a stick relay normally energized over stick circuit means including a front contact of said stick relay and a contact operated by said dual selector and closed only when said dual selector conditions said switch for operation by said machine, a polarized control relay, means controllable from a point 20 remote from said switch for positioning the polar armature of said control relay, a pick-up circuit for said stick relay including a winding of said stick relay and said selector lever contact and contacts operated respectively by said switch and 25 said polarized relay, said pick-up circuit being completed only when said selector lever contact is closed and said switch and the polar armature of said polarized control relay are in positions of agreement, and means for causing said switch 30 machine to operate said switch to a position in agreement with the polar armature of said polarized control relay only when said stick relay is picked up.

2. In a train dispatching system for railroads, 40 in combination, a dispatcher's office, a crossover located at a remote point and having a track switch at each end thereof, a switch machine provided for each track switch and each having a dual selector operable to one position for conditioning the associated switch for manual operation and to another position for conditioning the associated switch for operation by said machine, a stick relay for each track switch normally energized over a stick circuit including its own 45 front contact and winding and a contact operated by the dual selector of the associated switch and which contact is closed only when said selector is in its said other position, a control relay of the polar stick type capable when deenergized 50 of maintaining its polar armature in its last operated position, a communication system extending from said dispatcher's office to said remote point and capable of positioning the armature of said control relay by energy momentarily applied in response to a control transmitted by said system, a pick-up circuit for each of said stick relays, each of said pick-up circuits including the winding of the associated stick relay and said contact of the associated dual selector and contacts operated respectively by said control relay and the associated track switch, said pick-up circuits being completed only when said contact of the associated dual selector is closed and the position of the associated switch agrees with the 55 position of the polar armature of said control relay, and circuit means for causing said switch machines to operate the associated switches to positions in agreement with the position of the polar armature of said control relay provided that said stick relays are picked up.

3. In a train dispatching system of the class comprising an office and a station interconnected by a communication system, a crossover at said station having a track switch at each end thereof, two switch machines one for each track switch and each provided with a dual selector for selectively conditioning the associated switch for operation manually or by said machine, two circuit controllers one operatively connected with each of said switches and each having one contact closed only when said switch is in one extreme position and another contact closed only when said switch is in the other extreme position, two stick relays one for each of said switches and each normally energized over a stick circuit including its own front contact and winding and a contact operated by the associated selector and closed only when said selector conditions the associated switch for operation by

the associated machine, a polarized control relay arranged to position its armature in response to energy momentarily applied to its winding when a control is received at said station over said communication system, circuit means including a front contact of each of said stick relays for causing said switch machines to operate said switches to positions of correspondence with the armature of said control relay, and a pick-up circuit for each of said stick relays including the winding of the stick relay and said contact of the associated selector and contacts operated respectively by said control relay and by the associated switch, each of said pick-up circuits being completed only when said contact of the associated selector is closed and the armature of said control relay and the associated switch occupy corresponding relative positions.

HENRY S. YOUNG.
